TIE PLATE AND RAIL CLIP COMBINATION

Victor C. Armstrong, Short Hills, N. J., assignor
to Poor & Company, New York, N. Y., a corpora-
tion of Delaware

Application June 24, 1938, Serial No. 215,667

5 Claims. (Cl. 238—349)

This invention relates to supporting and retaining means for railway rails, and has particular reference to a tie plate having a novel upstanding lug formation with which to engage a rail retaining clip, and to a rail retaining clip constructed in a novel manner to be engaged with and held by said lug in holding relationship to the rail.

Generally speaking, the object of the invention is to provide a tie plate and rail retaining clip combination which is cheap and easy to produce and install and in which the clip serves effectively to retain the rail on the tie plate and, at the same time, permits the upward portions of the natural wave motion of the rail to pass through the latter substantially without being transmitted to the tie plate and through the latter to the tie, whereby disadvantageous "pumping" of the tie in the road bed is substantially eliminated.

According to the invention, the upstanding lug of the tie plate is in the form of a tongue-like portion of the tie plate bent upwardly therefrom and is provided at its top with an enlargement or head for interlocking cooperation with the rail retaining clip to hold the latter in assembly with the tie plate, and in this connection a special object of the invention is to bend said lug from the tie plate in a manner such that the free or upper end of the lug is comprised by a portion 30 of the usual rail abutting shoulder of the tie plate, whereby there is provided in the upper end of the lug the required amount of metal from which to form the enlargement or head thereof.

Another special object of the invention is to provide, for interlocking cooperation with a tie plate lug of the character mentioned, a rail retaining clip which may practically and economically be formed from flat stock simply by a bending operation, or operations, and which embodies a construction such that, when it is operatively engaged with the tie plate lug, it is held securely in rail retaining position thereon.

With the foregoing and other objects in view, which will become more fully apparent as the nature of the invention is better understood, the same consists in the novel features of construction, combination and arrangement of parts as will be hereinafter more fully described, illustrated in the accompanying drawings and defined in the appended claims.

In the accompanying drawings, wherein like characters of reference denote corresponding parts in related views:

Figure 1 is a fragmentary end elevation of a tie plate and rail retaining clip combination con-

structed in accordance with one practical embodiment of the invention.

Figure 2 is a plan view of the Fig. 1 construction.

Figure 3 is a view similar to Fig. 1 illustrating an alternative form of clip.

Figure 4 is a view similar to Fig. 1 illustrating an alternative form of the tie plate lug and another alternative form of clip for interlocking with said tie plate lug; and

Figure 5 is a section on the line 5—5 of Fig. 4.

Referring to the drawings in detail, A designates, generally, a tie plate of a well known type which is designed to be superimposed upon a tie and to be fastened thereto in any suitable manner to serve as a seat for a rail, designated generally as B, and which, in accordance with common practice, is provided with an upstanding rib 10 providing a shoulder or abutment engageable by the edge of the rail flange 11 to hold the rail 20 against outward or inward movement, as the case may be.

In accordance with the invention, the tie plate A is provided, at a point suitably spaced outwardly from the rib 10, with an upstanding lug 12 which 25 may be of any suitable height and width and which is provided at its top with an enlargement or head 13, illustrated in the present instance as being of substantially cylindrical shape in cross section and as extending horizontally from end 30 to end of the lug parallel to the rib 10. Further in accordance with the invention, there is provided a rail retaining clip C which may be formed economically from sheet stock, such as spring 35 steel, by a simple bending operation, or operations, and which comprises, primarily, an eye portion 14 for interlocking cooperation with the upper or headed portion of the lug 12, and a resilient finger 15 extending inwardly from said eye portion to overlie the rail flange 11, thereby to yieldably hold the rail against upward movement from its seat on the tie plate A.

The eye portion 14 of the clip C is substantially in the form of a hollow cylinder longitudinally slotted at its bottom, and is of such normal size 45 that when it is pressed or driven downwardly over the head 13 of the lug 12, or is operatively engaged with said lug by being moved endwise relative thereto, its side portions 16 are more or less sprung apart so that it tightly grips the head of 50 said lug. Moreover, the side portions 16 extend downwardly from the eye proper sufficient distances to engage the inner and the outer faces of the lug 12 below the head 13 of said lug, so that when the clip is operatively mounted on the lug 55

it is effectively held against rotation relative thereto. Therefore, the finger 15 is maintained operatively positioned in overlying relationship to the rail flange, either normally in contact therewith or normally spaced slightly thereabove, as may be desired, and serves to yieldably hold the rail against upward movement relative to the tie plate.

- Obviously, the clip C may have a variety of forms. For example, Fig. 1 of the drawings illustrates that the inner side portion of the eye 14, after being extended downwardly for engagement with the inner face of the lug 12 directly below the head 13 of said lug, extends upwardly and inwardly in the form of a U-bend 17, thence inwardly and downwardly in the form of an inverted U-bend 18, and finally inwardly at an upward inclination corresponding to the upward and inward inclination of the upper face 20 of the rail flange so as to flatly engage the latter; Figure 3 illustrates that the inner side portion of the eye 14, after being extended downwardly for engagement with the inner face of the lug 12 below the head 13 of said lug, extends upwardly and inwardly in the form of a U-bend 17', thence inwardly and downwardly in a relatively long arc 18' only the free or inner end of which engages the upper face of the rail flange; and Figure 4 illustrates a form similar 30 to the form illustrated in Fig. 1, but which differs therefrom in that the inverted U-bend, designated as 18', is flatter than the U-bend 17 and in that the portion of the finger which flatly engages the rail flange is of lesser length than 35 the corresponding portion of the finger of the Fig. 1 form. Moreover, Figs. 4 and 5 illustrate that the lug 12 may be provided with a slot or recess 19 below the head 13 thereof, and that the outer portion of the eye 14 of the clip may 40 have a tongue or tab 20 to engage in said slot or recess to prevent loss of the clip from the lug and to assist in holding the clip against rotation relative to the head of the lug. In all 45 cases, the U-bends joining the rail flange contacting portion of the finger of the clip with the eye of the clip afford resiliency beyond that afforded by the inherent resiliency of the spring steel or other material from which the clip is formed, so that, while the rail is held effectively 50 against excessive upward movements relative to the tie plate, it may, nevertheless, rise freely within a limited extent relative to said tie plate to permit its natural wave motion to pass freely therethrough.
- 55 Regarding the lug 12, this may be formed on the tie plate in any preferred manner. Preferably, however, for the sake of simplicity and economy in the production of the tie plate, it is in the form of a tongue bent upwardly from said plate. Moreover, while said lug may be bent upwardly from any desired portion of the tie plate, it preferably is bent from a portion of said plate such that its top portion is comprised by a removed portion of the rib 10. Because of this, 60 the removed portion of the rib 10 affords the necessary excess of metal in the top portion of the lug from which to form the enlargement or head 13 in a very simple forging or pressing operation.
- 70 Only one end portion of the tie plate and the related rail clip have been illustrated in the drawings. It will be understood, however, that the construction shown may be duplicated at the other end of the tie plate if desired.

Both the present tie plate and clip are comparatively cheap and easy to produce, the clip may readily and easily be applied to the tie plate lug, and when applied thereto it very effectively performs its intended function, as will be evident from the drawings.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:—

1. In combination, a tie plate, a rail seated thereon, a lug rising from the tie plate and having an enlarged head, and a rail retaining clip including a resilient eye portion of substantially the same interior cross sectional size and shape as the head of said lug embracing the head of said lug and having opposite side portions engaging opposite faces of said lug below the head thereof, whereby the clip is held in assembly with one of said eye side portions being 25 reversely bent upon itself to provide against rotation relative to the lug, and a resilient finger extending from said eye portion into overlying relationship to the rail flange.

2. In combination, a tie plate, a rail seated 30 thereon, a lug rising from the tie plate and having an enlarged substantially cylindrical head extending parallel to the rail, and a rail retaining clip including a substantially cylindrical resilient eye portion, of substantially the same interior cross sectional size and shape as the head of said lug, embracing said head and having opposite side portions extending below said head and engaging the inner and the outer faces of 35 the lug below the head thereof to hold the clip against rotation relative to the lug, one of said eye side portions being reversely bent upon itself 40 to provide a resilient finger extending from said clip into overlying relationship to the rail flange. 45

3. In combination, a tie plate, a rail seated thereon, a lug rising from the tie plate and having an enlarged substantially cylindrical head extending parallel to the rail, and a rail retaining clip including a substantially cylindrical resilient eye portion contractively embracing said head and having inner and outer side portions extending below said head and respectively engaging the inner and the outer faces of the lug below the head thereof whereby the clip is held 55 in assembly with and against rotation relative to the lug, the inner side portion of said clip eye being bent inwardly and upwardly and being then extended into overlying relationship to the rail flange.

4. The combination as set forth in claim 3 in which the lug is provided with a recess, and in which the outer side portion of the clip eye is provided with a tongue disposed in said recess.

5. A tie plate having a rib providing a rail abutment and an upstanding lug provided with an enlarged head with which to engage a rail retaining clip, said lug being bent upwardly from the tie plate and having the metal of its enlarged head comprised by a portion of the rib of said tie plate removed from its normal location by bending of the lug from the tie plate.

VICTOR C. ARMSTRONG.
